UNITARY CORONA REACTOR INCLUDING OPPOSED PLANAR NON-VITRIC DIELEC- TRIC WALLS

William R. Browne, Scotia, and John E. McNamara,
Schenectady, N.Y., assignors to General Electric Com-
pany, a corporation of New York

Filed May 10, 1965, Ser. No. 454,627
3 Claims. (Cl. 204—312)

ABSTRACT OF THE DISCLOSURE

A corona reactor is disclosed which is formed as a single unitary structure by a simple molding operation from a moldable, dielectric material such as a ceramic or synthetic resin which is chemically inert with respect to the reactant to be treated therein. The reaction chamber comprises inlet and outlet means with a reaction zone therebetween, the reaction zone being defined by a pair of parallel, substantially rectangular wall portions having smooth interior face portions spaced a constant distance apart, the spacing dimension being much smaller than any lateral dimension of the rectangular wall portion. The outer surfaces of the rectangular wall portions have electrode supporting portions which are substantially parallel to each other and to the corresponding inner surface of the rectangular wall portions.

Our invention relates to a unitary corona reactor.

When two bare electrodes separated by a gaseous media are subjected to a potential difference, an electric arc may be generated between the electrodes by ionization of the gas. An electric arc is a high current, low voltage electrical phenomenon visually discernible by its limited areal extent and sharp boundaries. If the pressure, and hence density, of the gaseous media lying between the electrodes is reduced well below atmospheric pressure, a potential difference applied to the electrodes will produce a glow discharge. A glow discharge is characterized by a soft diffused appearance extending over a substantial area and lacking distinct boundaries. Such discharge is formed by electrically energizing gaseous particles by direct contact with the electrodes. The low pressure, however, prevents the formation of a gaseous ionic conducting bridge between the electrodes which would produce an electric arc.

A third and completely distinct type of electrical discharge is termed a corona discharge. When two electrodes are separated by a gaseous media and also by one or more dielectric barriers, the application of an alternating current to the electrodes will capacitively excite the gaseous media to produce a corona discharge therein. Such type discharge differs from an electric arc in being a high voltage, low current phenomenon. Further, corona discharge, while visually similar to glow discharge, differs markedly therefrom in that corona discharge propagation does not require direct contact between the electrodes and the gaseous media or reduced pressures to avoid arcing. Additionally, unlike an electric arc or a glow discharge, a corona discharge can be generated only by an electrical energy source of alternating current.

Various forms of apparatus have been constructed for treating gases and liquids in the presence of a corona discharge. The earliest and still most widely used forms

2

of corona reactors were constructed from glassware. In considering operations beyond the laboratory level, however, such reactors present serious problems stemming from the propensity toward breakage of glassware, including safety hazards to personnel and equipment, the requirement of special care in handling and mounting, the inability of glassware to reliably withstand over-all high temperatures or localized elevated temperature, the risk of placing a process off-stream, etc.

For industrial environments, more rugged types of corona reactors have been proposed. Such reactors typically include a housing forming a chamber or plenum to confine the gaseous media in which the corona is to be propagated, electrodes mounted within the housing, units to mount electrodes in the desired relation to the housing and to each other, dielectric barriers either attached to the electrodes or interposed therebetween by separate mountings, and, in dynamic reactors, guides to direct flowing reactants through the corona. While such corona reactors avoid the disadvantages encountered in using laboratory glassware, such reactors heretofore produced have been relatively expensive due to their unduly complex and cumbersome structural forms.

It is an object of our invention to provide a simple, unitary, economically fabricated corona reactor.

It is another object to provide a corona reactor of rugged construction.

It is an additional object to provide a corona reactor capable of operating at elevated temperatures with minimal risk of damage.

It is a further object of our invention to provide a corona reactor which can be formed by a simple molding operation.

These and other objects of our invention are accomplished by providing a dielectric corona reactor housing having first and second opposed, planar, substantially parallel wall portions and first and second electrodes mounted exteriorly of said housing and adjacent said first and second wall portions, respectively.

Our invention may be better understood by reference to the following detailed description considered in conjunction with the drawings, in which

FIGURE 1 is a front elevation, partly in section, of a corona reactor constructed according to our invention;

FIGURE 2 is a side elevation, partly in section, of the corona reactor of FIGURE 1;

FIGURE 3 is a front elevation, partly in section, of a modified form of corona reactor; and

FIGURE 4 is a side elevation, partly in section, of the modified form of corona reactor of FIGURE 3.

Referring to FIGURES 1 and 2, a corona reactor 1 is connected by a coupling collar 2 to an inlet conduit 3 and by a coupling collar 4 to an outlet conduit 5. The corona reactor is comprised of a dielectric housing 6 formed of an easily fabricated, non-vitric dielectric material such as, for example, a synthetic resin. The housing includes a first wall portion 7 which is of uniform thickness. Directly opposite and spaced from the first wall portion is a similar substantially parallel wall portion 8. Each of first and second wall portions 7 and 8 merge smoothly into surrounding wall portions 9 and 10, respectively, of greater thickness than the wall portions 7 and 8. In the area where the wall portions 7 and 8 merge into the surrounding wall portions 9 and 10, respectively, an arcuate surface 11 is formed on the exterior surface

of the housing. The surrounding wall portions 9 and 10 are joined together by integrally formed side walls 12 and 13.

Mounted adjacent the wall portions 7 and 8 are electrodes 14 and 15, respectively. Electrode 14 is provided with a planar face portion 16 conforming to the exterior surface of the wall portion 7 and an arcuate perimeter portion 17 conforming to the arcuate surface 11. Electrode 15 is similarly provided with a planar face portion 18 and an arcuate perimeter portion 19. The electrode may be formed as separate metallic elements pressed against or adhered to the housing or may be formed as a conductive coating on the exterior of the housing such as a conductive paint, electrodeposited metal, etc.

It is noted that the electrode 14 and the wall portions 7 and 9 cooperate to form an electrode assembly including an electrode and dielectric barrier. The electrode 15 and the wall portions 8 and 10 cooperate to form a similar electrode assembly. The sidewalls 12 and 13 act as means for joining electrode assemblies in spaced relation through the dielectric barriers.

The wall portions 9 and 10 and side walls 12 and 13 converge at each end of the housing to form inlet and outlet necks 20 and 21. The space between the walls 12 and 13 and wall portions 7 and 8 forms a chamber 22 in which a corona may be propagated. An inlet conduit 23 may be connected to conduit 3 to introduce a material to be treated into the corona within the chamber 22. Material is exhausted from the chamber 22 through neck 21 and outlet conduit 5 connected to conduit 24. A portion of the material exhausted from the corona reactor may be recirculated by means of conduit 25 extending from outlet conduit 5 to inlet conduit 3 and having a pump means such as 26 connected therein.

A potential is supplied to the electrodes from a source of alternating current 27. The alternating current source is connected to a tuning circuit schematically shown at 28. The tuning circuit in its three simplest forms may be comprised of a variable capacitance and inductance in shunt, a variable capacitance in shunt and an inductance in series, or a variable capacitance in series and an inductance in shunt. Other tuning circuits are of course known and utilizable. Electrical leads 29 and 30 extend from the tuning circuit to electrodes 14 and 15, respectively.

In operation, the corona reactor 1 is supplied with a material to be treated through conduits 23 and 3. Subsequent to purging the system, an electrical potential is applied across the electrodes 14 and 15 through leads 29 and 30. A corona discharge is formed within the chamber 22 between the electrodes and in intimate contact with the material to be treated. The arcuate perimeter portions 17 and 19 of the electrodes 14 and 15 provide for a rapid decay in electric field strength beyond the edges of the electrodes thereby preventing power losses through stray edge currents not contributing to the propagation of the corona discharge. The tuning circuit 28 provides for electrical load circuit power factor correction so that the electrical energy source 27 sees only the resistive load represented by the corona power.

The material undergoing treatment exhausts from the corona reactor through neck 21 and conduit 5. The material is subsequently transported to the next process phase through conduit 24. If desired, a portion of the material treated may be recirculated through conduit 25 through operation of pump means 26.

FIGURES 3 and 4 illustrate a second exemplary form of corona reactor 100. The reactor includes a unitary molded ceramic housing 101. The housing terminates at its upper extremity in a flange 102. The lower end of the housing is shown provided with a port 110.

A tapered fitting 103 is shown connected to the upper end of the corona reactor having a flange 104 at one end and a ring coupling 105 at the other end. An annular sealing ring 106 is mounted between flanges 102 and 104.

The flanges are pressed together to compress the sealing

ring by means of clamping rings 107 and 108 joined by tie bolt assemblies 109. The ring coupling connects the tapered fitting 103 to a fluid conduit.

A fluid conduit 111 is shown sealed against the housing within port 110 by an O-ring seal 112. The O-ring seal is held in position on the conduit by shoulders 113 and 114. The tapered fitting 103, outlet conduit 111, and attendant elements form no part of the corona reactor 100 but are merely exemplary of the type of connection means which may be employed in combination with the corona reactor.

The housing 101 of the reactor includes spaced, opposed, substantially parallel front and rear wall portions 115 and 116 which are joined at their edges by side wall portions 117 and 118. Electrodes 119 and 120 are mounted adjacent the wall portions 115 and 116, respectively. The electrode 120 is connected to ground by lead 121. The electrode 119 is connected to a tuning circuit 122 schematically shown by a lead 123. The tuning circuit is connected to ground by lead 124 and to a source of alternating current 125.

The corona reactor 100 may be operated similarly to the corona reactor 1. While reactor operation has been disclosed in terms of continuous circulation of reactants, it is contemplated that the reactors may be used to treat fluids statically contained therein. In certain instances, it may be desired to treat a fluid contained in a dielectric package without removing the fluid from the package. The corona reactor 100 is particularly amenable to such use. In certain instances, it may be desired to introduce a solid substrate into the corona reactor to be coated by fluid undergoing corona treatment. Also, it may be desired to continuously pass a substrate through the reactor for treatment or coating within the corona zone. In such instance, the configuration of the inlet and outlet openings of the housing may be formed to correspond to that of the substrate. As previously indicated, the inlet and outlet couplings of the corona reactor may be chosen from a wide variety of known coupling structures. In certain applications, it may be desired to purge the reactor with a fluid other than the fluid to be treated, such as helium, argon, nitrogen, etc. Provision for the circulation of a purging fluid may be made by providing suitable connections to the inlet and outlet conduits or by providing additional inlet and outlet ports in the housing. While the reactor electrodes are shown mounted exterior of the housing, it is of course contemplated that the electrodes may be encased within the housing according to the teaching of our abandoned, previously filed application Ser. No. 409,199, filed Nov. 5, 1964.

Numerous additional modifications will be readily suggested to those skilled in the art. For this reason, it is intended that the scope of our invention be determined by reference to the following claims.

What we claim as new and desire to secure by Letters Patent of the United States is:

1. A unitary corona reactor comprising a hollow housing integrally cast from a non-vitric dielectric material which is chemically and physically inert with respect to the environmental conditions of the reaction, said housing comprising inlet means for the reactant, a reaction chamber, and outlet means for the reaction product, said reaction chamber comprising a pair of opposed, spaced, substantially parallel, planar wall portions, said wall portions each having opposed electrode supports formed by substantially rectangular recesses in their outer surfaces, each of said recesses being composed of a planar recessed surface having an arcuate perimeter portion curving outwardly of said planar recessed surface, said planar recessed surfaces being substantially parallel to each other and to the inner surfaces of said planar wall portions, and electrodes comprising electrically conductive layers coating the surfaces of said recessed portions including said arcuate perimeter portions.

2. The corona reactor as recited in claim 1 wherein

the space between said wall portions defined by said opposed electrodes comprises a substantially rectangular reaction zone wherein said space has a transverse dimension substantially smaller than any lateral dimension of said reaction zone.

5. The corona reactor as recited in claim 1 wherein said electrically conductive layers comprise coatings adherently deposited on the surfaces of said recesses.
